UNITED STATES PATENT OFFICE.

HERBERT JAMES CLEMENT WELLS, OF NEW YORK, N. Y.

REFRIGERATOR CONTROL.

Application filed January 24, 1922. Serial No. 531,429.

To all whom it may concern:

Be it known that I, HERBERT J. C. WELLS, a subject of the King of Great Britain, residing at New York, N. Y., have invented a 5 new and useful Refrigerator Control, of which the following is a specification.

Certain types of automatic refrigerators for domestic and other purposes employ compressors and cooling systems controlled 10 by thermostats subject to the temperature of a refrigerated chamber. An ordinary thermostat develops only a relatively small power with limited changes in temperature permissible. As a consequence, it is customary to 15 employ electric relays or other complicated means to obtain sufficient power to operate the motor and the valve in the cooling water supply. I propose to develop the power necessary from the water supply or from some 20 circulating medium.

In carrying this out I utilize a thermostatic device for partially closing a valve in the water supply line and thus backing up the water into a tilting or float chamber, 25 which in turn operates the main valve to shut off the water supply and a switch to open the motor circuit.

Fig. 1 is an end view of apparatus embodying the improvements of my invention. 30 Fig. 2 is a side view of the same.

A conduit 5 is provided for the cooling water. In this conduit are located two valves 6 and 7. The valve 6 has a stem 8 and is normally closed and is adapted to be opened 35 by vapor pressure developed in the thermostat 9 and the expansible chamber 10 and connecting pipe 11. The thermostat 9 is located in the refrigerated chamber.

The main valve 7 has a stem 12 with stops 40 13 and 14. This valve is operated by hydraulic means, such for instance, as the tilting reservoir 15 pivoted at 16 and having an arm 17 adapted to engage the stops 13 and 14 on the valve stem. In the form shown the 45 lever 18 is hinged to the reservoir 15 and supported on the upper end of the rocker arm 19. The weight 20 is adapted to be adjusted along the lever 18 and tends to hold the reservoir 15 in the position shown in the drawings. The bottom of the reservoir is connected by a pipe 21 to the cooling water conduit 5 at some point between the valves 6 and 7. The pipe 21 is connected to the reservoir 50 in such a manner that it will not interfere with the tilting action. For this purpose, in the form shown, a part of the pipe 21

adjacent the reservoir is flexible. A switch 22 is intended to control the motor circuit and is provided with an operating push button 23 adapted to be operated by one of the 60 arms 19.

When the thermostat is at a temperature above its predetermined valve closing point, the valves 6 and 7 are open and the cooling water freely circulates through the conduit 65 5. When the temperature in the refrigerated chamber falls to a predetermined point, say 38° F., the valve 6 begins to close. The slightest closing movement tends to throttle the water slightly and backs up the pressure 70 in the conduit 5, so that water begins to flow through the pipe 21 into the reservoir 15 tending to fill it. When the filling has proceeded to a point sufficient to overcome the balance of the weight 20, the tank will swing 75 forward and downward and its arm 17 striking against the stop 14 will forcibly and suddenly close the valve 7, thus entirely shutting off the cooling water. Simultaneously the rocker arm 19 will operate the switch 22 so and break the circuit and stop the electric motor. The cooling effect is, of course, not instantly checked, but continues to affect the thermostat, causing the valve 6 to close, and preventing the water from flowing out from 85 the reservoir 15. When the temperature of the thermostat begins to rise, the valve 6 will immediately begin to open, so that the reservoir or tank 15 will gradually empty. When the weight 20 overbalances the weight 90 of the reservoir, the reservoir will tilt up again and suddenly open the valve 7 and at the same time automatically allow the switch 22 to close its circuit and start the motor. Cooling water then flows through the conduit 95 5 until the cycle is completed.

It will be observed the thermostat has very little work to do, as it is simply necessary to move the valve sufficiently to partially throttle the water supply. The real work of 100 closing the water line is being done by the swinging tank which also operates the electric switch. Furthermore, when the thermostatic valve is opened, it is exposed to very slight water pressure, namely, merely to that of the height of water in the reservoir 15. It is thus that a thermostat having a maximum operating power on slight temperature changes is able to control effectively 105 the operation of the entire refrigeration apparatus, maintaining the temperature of the refrigerator chamber within a closer range 110

than is possible with other existing devices with which I am familiar.

Some of the elements of this combination are well known and are not separately claimed. On the other hand, they may be varied in design, provided the action obtained is that claimed.

I claim:

1. A refrigerator control apparatus comprising the combination with a water supply conduit, two shut-off valves in said conduit, thermostatically controlled means subject to the temperature of the refrigerator for operating one of said valves, and liquid operated means for positively operating the other valve, said latter means being operated automatically.

2. A refrigerator control apparatus comprising a liquid supply conduit, two valves therein, thermostatic means subject to the temperature of the refrigerator for controlling one of said valves, a hydraulic device for operating the other valve and a connection from said hydraulic device to said conduit between said valves.

3. Control apparatus comprising a liquid supply conduit, a main valve therefor, a thermostatically operated valve for said conduit for throttling the liquid therein, means for passing water through said conduit, said means including an electric motor, an electric switch for controlling the circuit through said motor and an hydraulically operated member connected to said conduit for operating said switch and said main valve.

4. A refrigerating apparatus including a liquid conduit, thermostatically controlled means subject to the temperature of the refrigerator for throttling liquid in said conduit, a main valve for said conduit, a movable tank for operating said valve, and a connection between said conduit and said tank so that, upon throttling the liquid, the tank will be filled and moved to close said main valve.

5. A refrigerating apparatus including a liquid supply conduit, a main valve therein, a tilting tank for operating said valve, a pipe connecting said conduit and said tank, and thermostatically controlled means subject to the temperature of the refrigerator for causing liquid to flow through said pipe

into said tank to operate the same and shut the main valve.

6. A refrigerating apparatus including a liquid supply conduit, a main valve therefor, a tilting tank for operating said valve, a pipe connecting said conduit and said tank, and thermostatically controlled means subject to the temperature of the refrigerator for controlling the flow of liquid into and out of said pipe and thereby controlling the closing and opening of said main valve.

7. A refrigerating apparatus including a liquid supply conduit, a main valve therefor, a tilting tank for positively operating said valve, and thermostatically controlled means subject to the temperature of the refrigerator for initiating the filling and emptying of said tank, means, including a motor for forcing liquid through said conduit, and a switch operable by the tilting of the tank to throw the motor into and out of operation.

8. A refrigerator control mechanism comprising a cooling water conduit, two valves located in said conduit, temperature controlled means for operating one of said valves, a movable tank connected to said conduit between said valves and an operative connection between said second valve and said tank whereby the closing of the first valve forces water to flow into said tank and the filling of said tank moves said tank to close said second valve and whereby the opening of said first valve allows said tank to drain and by a subsequent movement to open said second valve.

9. A refrigerator control mechanism comprising a cooling liquid conduit, two valves located in said conduit, temperature controlled means for operating one of said valves, a movable tank connected to said conduit between said valves and an operative connection between said second valve and said tank whereby the closing of the first valve forces water to flow into said tank and the filling of said tank moves said tank to close said second valve and whereby the opening of said first valve allows said tank to drain and by a subsequent movement to open said second valve, means, including a motor, to cause liquid to flow through said conduit, and a switch operated by said tank to throw said motor into or out of operation.

HERBERT JAMES CLEMENT WELLS.
